US0D1061962S

(12) **United States Design Patent** (10) Patent No.: **US D1,061,962 S**
Chen et al. (45) Date of Patent: ** Feb. 11, 2025

(54) **LED LIGHT**

(71) Applicants: **Shenzhen Qiyan Technology LTD**,
Shenzhen (CN); **Shenzhen Intellirocks
Tech. Co., Ltd.**, Shenzhen (CN)

(72) Inventors: **Chaogou Chen**, Guangdong (CN);
Wenlong Wu, Guangdong (CN)

(**) Term: **15 Years**

(21) Appl. No.: **35/519,026**

(22) Filed: **Sep. 13, 2023**

(80) **Hague Agreement Data**

Int. Filing Date: **Sep. 13, 2023**

Int. Reg. No.: **DM/232918**

Int. Reg. Date: **Sep. 13, 2023**

Int. Reg. Pub. Date: **Nov. 17, 2023**
